ATTORNEY

UNITED STATES PATENT OFFICE.

WILLARD HOUGHTON, OF SEATTLE, WASHINGTON.

CAR-STAKE.

1,101,185.

Specification of Letters Patent. Patented June 23, 1914.

Application filed January 22, 1914. Serial No. 813,609.

To all whom it may concern:

Be it known that I, WILLARD HOUGHTON, a citizen of the United States, residing at Seattle, in the county of King and State of Washington, have invented certain new and useful Improvements in Car-Stakes, of which the following is a specification.

This invention relates to releasable or tiltable stakes for logging cars; and its object 10 is the perfecting of such devices to render the same more efficient in operation and convenient to trip for the discharge of logs from a car.

The invention consists, primarily, of a 15 main stake which is tiltably secured to the end of a bunk frame and serves to support a supplementary stake or stanchion and which is automatically released from the main stake when the latter is swung clear 20 of the load.

The invention further consists in the novel construction and combination of parts, as will be hereinafter described and claimed.

In the accompanying drawings, Figure 1 25 is a transverse vertical sectional view of a portion of a flat-car with my invention applied thereto, with the bunk shown in section. Fig. 2 is an underside plan view partly broken away of the bunk and associated parts. Fig. 3 is an end elevational 30 view with the parts in operative position, as illustrated at the left side of Fig. 1. Fig. 4 is a fragmentary plan view. Fig. 5 is a detail plan view of the means for securing 35 the operating lever of one of the stakes.

Referring to the drawings, the reference numeral 10 designates the deck of a flat car and 11 are the sill members for the same.

12 indicates a bunk which, as shown, is 40 comprised of side walls 13 having flanges 14 at their lower edges to afford a stable seat upon said car-deck and to which the bunk is rigidly secured in any well-known or suitable manner.

45 The bunk's side walls 13 are connected near their upper edges by a horizontal wall 15 and also at their ends by bridge-pieces 16 which are located at or below the upper surface of the deck. The deck is desirably 50 constructed or adapted to afford an opening immediately below the space between

the bunk-walls and to a short distance to each side of the same, as indicated in Fig. 3. Extending from each of the bunk walls near the end thereof is a bracket 17. 55

At each end of the bunk is a stake 18 which is pivotally connected by a bolt 19 to the bunk at a distance from the end of the latter. The outer end of a stake is held up in operative position by means of 60 a block 20 which, in turn, is supported by the adjacent brackets 17. When the block is withdrawn from such brackets the outer end of a stake is unsupported and falls down into the position corresponding to that in 65 which the stake is represented by full lines at the right side of Fig. 1.

A block 20 is connected to the end of a pull-rod 21 whose other end is connected to a lever 22 which is fulcrumed to a staple 23 70 depending from bunk-wall 15 in proximity to the opposite end of the bunk from the block.

As illustrated, a lever 22 extends below the sills 11 of the car, and is conveniently 75 controlled by an attendant from the opposite side of the car from a stake which is to be tripped. For securing the lever to hold the block in position to support a stake, I provide a bar 24 having a recess 80 25 which terminates at a shoulder 25¹ against which the lever abuts, see Fig. 5, when the block is upon the respective brackets 17.

26 is a spring which serves to prevent any accidental lateral movement of the lever 85 such as would allow it to be withdrawn from the shoulder 25.

When a stake is down, as indicated by full lines at the right of Fig. 1, it is moved by the attendant, standing at that side of 90 the car, into operative position by swinging the same outwardly and upwardly to occupy the position in which it is indicated by broken lines A in the view.

The attendant holding the stake in its 95 upright position with one hand, with his other hand grasps the block and introduces it below the heel 18¹ of the stake and onto the brackets. The block thus handled causes the connected rod 21 to swing the respective 100 lever 22 into position whereat the spring 26 will thrust it into the recess 25 where-

- upon the bar-shoulder 25¹ will serve to hold the block upon the brackets until its withdrawal therefrom is intentionally made by an attendant from the remote side of the car.
- 5   Included in the invention are stanchions 27 which, upon occasion, are employed with the aforescribed stakes to serve as extensions for use where a high load of logs is to be carried on a car.
- 10   A stanchion is desirably formed of a rail having a central "web" element 28 and lateral flanges 29 at one edge thereof and of such widths as to permit their entering the space between the bunk-walls 13 and into 15 juxtaposition with a stake.
- Rigid with the stanchion is a strap 30 having its aperture 31 adapted to fit loosely about a projection 32 provided on the upper end of a stake and allow the strap to seat 20 upon a shelf 33 formed in the stake at the base of said projection. By such devices, the stanchion is hung upon and sustained by a stake and when the latter is tripped and swings downwardly, the stake projection 32, 25 by reason of its loose fit with the strap, will be readily withdrawn. I prefer, moreover, to provide devices supplementary to the referred to sustaining means for retaining the stanchion in upright position. To which 30 end, hooks 34 are pivotally connected to the bolt 19 at opposite sides of a stake and are adapted to engage over ears 35 which protrude from the sides of the stanchion flanges, as best shown in Fig. 3.
- 35   The hooks 34 serve to prevent the lower end of a stanchion from swinging outwardly from between the bunk-walls 13. Ears 36 may advantageously be provided upon a stanchion to engage against the underside 40 of the bunk to prevent any accidental raising of the stanchion where the latter is in operative position as, for example, on an unloaded car when the same travels over a rough section of track.
- 45   To couple a stanchion to a stake, the stanchion is first raised in an inclined position with the ears 35 below the bills 34¹ of the hooks 34, and the ears 36 against the end of the bunk, and when the bracket is 50 above the stake projection 32, the stanchion is lowered to have the strap seated upon the stake shoulder 33, whereupon the lower end of the stanchion is shoved into the housing therefor between the bunk-walls 13.
- 55   Having described my invention, what I claim, is—
1. In a device of the class described, the combination with a car-bunk provided with bracket elements upon the side walls thereof, of a stake pivotally connected to the bunk at a distance from said bracket elements, and means removably seated upon the bracket elements for releasably holding said stake in upright position.
  2. In a device of the class described, the combination with a car-bunk, a stake pivotally connected to the bunk, a block supported by bracket-pieces provided on the bunk for supporting the stake in upright position, and a rod connected to the stake and operated from the end of the bunk remote from the stake whereby the block may be dislodged for releasing the stake.
  3. In a device of the class described, the combination with a car-bunk, and a bolt secured to the side walls of said bunk, a stake pivotally connected to said bolt, of a stanchion, a strap provided intermediate the length of the stanchion and engageable upon a shelf provided on the stake whereby the stanchion is supported by the stake, and means connecting the stanchion with the bunk whereby the lower end of the stanchion is prevented from swinging outwardly with respect to the bunk.
  4. In a device of the class described, the combination with a car-bunk, a bolt secured to the bunk, a stake pivotally connected to said bolt, and removable means engaging under the heel of the stake for supporting the same in upright position, of a stanchion and means provided on the stanchion for engaging the top of the stake to thereby suspend the stanchion when the stake is in an upright position.
  5. In a device of the class described, the combination with a car-bunk, a stake pivotally connected to the bunk, said bunk being provided adjacent its upper end with a shelf and a projection extending above the shelf, and means for releasably securing said stake in upright position, of a stanchion, and a strap rigidly connected to the stanchion and adapted to fit loosely over the aforesaid projection and be seated upon said shelf for supporting the stanchion.
  6. The combination with a car-bunk having bracket-elements interiorly thereof, a stake, a bolt extending through the bunk for pivotally connecting the inner end of the stake to the bunk, a block arranged to seat upon the bunk, bracket elements for supporting the outer end of the stake, a pull-rod connected to said block, a lever connected to said rod for withdrawing the block from said bracket elements whereby the outer end of the stake is free to swing downwardly between said bracket elements, and means for securing the lever in position to maintain the stake-supporting block in operative position.
  7. The combination with a car-bunk, a stake, a bolt secured in fixed position to the bunk for pivotally connecting the inner end of the stake to the bunk, means for releasably supporting the outer end of the stake, a stanchion supported by the stake, and a hook pivotally connected to said bolt and

engaging the stanchion whereby the same is held in juxtaposition with the stake when the latter is in upright position.

8. In a device of the class described, a car-stake pivotally connected to the bunk for swinging movements only and provided with a shoulder adjacent to its upper end, and a stanchion provided with releasable means

for engaging said stake and adapted to seat upon the stake shoulder. ¹⁰

Signed at Seattle, Wash., this 15th day of January, 1914.

WILLARD HOUGHTON.
